US0D1056263S

(12) **United States Design Patent** (10) **Patent No.:** **US D1,056,263 S**
(45) **Date of Patent:** ** *Dec. 31, 2024

(54) **STRING LIGHT**

(71) Applicant: **Linhai Lize Photoelectric Technology Co., Ltd.**, Taizhou (CN)

(72) Inventor: **Lianny Ye**, Taizhou (CN)

(73) Assignee: **Linhai Lize Photoelectric Technology Co., Ltd.**, Taizhou (CN)

(*) Notice: This patent is subject to a terminal disclaimer.

(**) Term: **15 Years**

(21) Appl. No.: **29/851,864**

(22) Filed: **Sep. 1, 2022**

(51) LOC (14) Cl. **26-04**

(52) U.S. Cl.

USPC **D26/25**

(57) **CLAIM**

The ornamental design for a string light, as shown and described.

DESCRIPTION

FIG. 1 is a front perspective view of a string light, showing my new design;

FIG. 2 is a front view thereof;

FIG. 3 is a rear view thereof;

FIG. 4 is an enlarged left side view thereof;

FIG. 5 is an enlarged right side view thereof;

FIG. 6 is a top view thereof; and,

FIG. 7 is a bottom view thereof.

The broken away symbols in the drawings indicate the appearance of any portion of the article between the broken away symbols form no part of the claimed design.

1 Claim, 7 Drawing Sheets
